DISPLAY CONTAINER

Robert I. Promisel, Winthrop, Mass.

Application January 26, 1949, Serial No. 72,879

4 Claims. (Cl. 217—11)

1

The present invention relates generally to containers, and in particular it relates to combined storage and display containers; that is, containers wherein material or articles may be disposed and/or displayed. More particularly, the present invention relates to box-like containers of the type which may be stacked vertically, one above the other.

One particular field of utility for the present invention is the bottled beverage field, wherein several bottles may be disposed within a carrier, and a number of carriers placed within the container for transportation from the site of manufacture to the ultimate retail seller. Carbonated beverages are bottled in six, eight, ten or twelve ounce bottles, and up to six of these bottles may be placed within a cardboard or metal carrier for easier handling by the ultimate purchaser thereof. For shipment from the bottler to the retail outlet, a number of these carriers are disposed within a wooden or metal crate, conventionally open at the top thereof. Access to these crates can be had only through the open top. Of course, to save floor space, a plurality of these crates or boxes are stacked one atop another, as high as is practicable in each individual instance. This method, however, presents considerable handling problems, because as the topmost crate is emptied of its contents, it must be removed from the stack and placed elsewhere before access can be had to the crate beneath it. Another disadvantage to this conventional crate or box is the fact that its contents can be viewed only when the crate top is below eye level.

The main object of the present invention, therefore, is the provision of an open topped crate or box (hereinafter referred to as a crate) which may be stacked readily, a wall portion of which crate can be swung away to permit the crate contents to be viewed at any level, the swung side being disposable atop the crate to aid in supporting additional crates thereon when stacked in vertical superposition.

Other, further and more detailed objects of the present invention will in part be obvious and in part pointed out specifically in connection with the following description of an illustrative embodiment thereof.

In the drawings annexed hereto, and forming a part hereof,

Figure 1 is an isometric view of one form of crate constructed according to and embodying the present invention;

Figure 2 is an isometric view of a plurality of 55 to be stacked thereon, as shown in Figure 2.

2

crates in accordance with the invention stacked one atop the other;

Figure 3 is a vertical section on the lines 3—3 of Figures 1 and 5;

Figure 4 is a section on the line 4—4 of Figure 2;

Figure 5 is a detail, enlarged, of the upper right hand corner of the crate;

Figure 6 is a detail, enlarged, of the front wall locking mechanism; and

Figure 7 is a vertical section on the line 7—7 of Figure 6.

The crate according to the present invention is indicated by the reference numeral 10, and 15 comprises an open topped rectangular casing having a floor 12, end or side walls 14, 14, a rear wall 16, and a front wall 18. The floor portion 12, end wall portions 14, 14, and rear wall portion 16, may be of conventional structure, secured together by nails, screws, bolts or the like. It is in structure connection and functioning of 20 the front wall panel 18 that the crate of the present invention departs from the conventional. The crate components may be formed of wood, 25 plywood, fiber board, metal or the like, as desired.

Front wall panel 18 is pivotally connected to end walls 14, 14, by double pintle hinges 20, 20 (see Figures 3 and 4), one leaf 22 of each hinge

30 20 being secured to both upper corners of the wall panel, with the other leaf 24 of the hinges being secured to the upper front edges of the end walls 14, 14. In the form shown, the double pintle 26 consists of a squared ring of suitable metallic material, although, as may be convenient, the double pintle may comprise an intermediate plate and separate pivot pins connecting the plate to the outer leaves 24, 26. In the drawings, however, the squared ring functions

35 similarly to permit front wall panel 18 to be swung outwardly away from the body of the crate and over onto the top of the crate, as in Figure 4 and the topmost crate of the stack in Figure 2. As seen in Figures 3 and 4, pintle portion 30 through loop 32 in leaf 22, and pintle portion 40 through loop 42 in leaf 24, are spaced apart by the leg components 50, 50 of ring 26. Legs 50, 50 are substantially equal in length to the thickness of wall panel 18 and the distance

45 between the top of end walls 14, 14 and the situs of hinge leaves 24, 24. With this proportioning of parts, when front wall panel 18 is swung up and over onto the top of crate 10, it will lie flatly thereon, to serve as a support for other crates 50

A spring latch 60 may be provided adjacent the bottom edge of panel 18, slidably receivable in socket 62 in floor 12 to lock the front panel 18 to the crate during shipment, or at other times as desired, and for ready pivoting thereof. Also, if desired, an inwardly opening registering recess 70 may be formed along each lateral edge of panel 18, in line with a headed member 72 projecting forwardly from the front edges of walls 14, 14 to accurately align the several parts 10 during handling or shipping of the crates.

With the box of the presently described construction, which may, but need not have, dividing partitions as 76 on the floor thereof, articles as carriers 80, 80 or otherwise may be disposed therein through the open top, or through the front (if open). A plurality of crates 10, 10 (four being shown in Figure 2) may be stacked atop one another, and if the front wall panel components thereof are swung over the top thereof, as shown, the contents of all the boxes can be seen easily, and may be removed from all the boxes without further disturbing the boxes or their stacked arrangement. When four conventional boxes are stacked atop one another, the contents of only the topmost box will be visible. When these contents are removed, the box must be removed from the stack and set aside in order to expose the next box to ready access for the viewing and handling of its contents. In this way, two stacks are set up, occupying twice as much space and requiring the expenditure of time and effort in the handling, all of which is obviated with the device of the present invention.

A stack of boxes according to the present invention may be as high as space permits, for access can be had to any box in the stack without disturbing any other box in the stack.

It is to be understood that my invention is not limited in use to the beverage field, but may be used in other fields as well. My invention is to be limited only by the scope of the appended claims.

I claim:

1. A device of the character described comprising a generally rectangular open-topped container having a bottom, end walls, a rear

wall, and a front wall, the front wall being pivotally secured to the end walls and being swingable outwardly from the casing to overlie the top of the casing and partially cover same resting flatly atop the end walls, thereby exposing the casing interior and contents to view through the front thereof whereby the front wall serves as a support for like containers stacked on top thereof.

2. A device of the character described as in claim 1, in which the pivotal securing of the front wall to the end walls is by double pintle hinges at the upper corners of the front wall and the upper front edges of the end walls.

3. A device of the character described as in claim 1, having lock means to releasably secure the front wall to the floor of the container.

4. A generally rectangular open-topped display container, having a bottom and four vertical wall components at right angles thereto, one of the vertical walls being pivotally connected to the walls on each side thereof, the pivotal connection being by double pintle hinges, one leaf of each of which is secured to the pivotal wall, the other leaf of each of which hinge is secured to the adjacent walls, the leaves being spaced apart sufficiently to permit the pivoted wall to swing outwardly from the casing and over atop the adjacent walls to rest thereon in parallelism to the bottom whereby said pivoted wall forms a support for like containers stacked on top thereof.

ROBERT I. PROMISEL.
